Specification for Design.

Patented Oct. 16, 1917.

Application filed July 13, 1917. Serial No. 180,458. Term of patent 7 years.

To all whom it may concern:

Be it known that I, JOSEPH F. JECKERT, a citizen of the United States, residing at Garfield, in the county of Bergen and State of New Jersey, have invented a new, original, and ornamental Design for Smokers' Outfits, of which the following is a specification, reference being had to the accompanying drawing, forming part thereof.

In the drawing the figure is a perspective view of the smoker's outfit.

I claim:—

The ornamental design for a smoker's outfit, as shown.

JOSEPH F. JECKERT.
